Arthur B. Jenkins.

ATTORNEY

UNITED STATES PATENT OFFICE

RALLSTON M. SHERMAN, OF GLASTONBURY, CONNECTICUT, ASSIGNOR TO THE SILENT GLOW OIL BURNER CORPORATION, OF HARTFORD, CONNECTICUT, A CORPORATION OF CONNECTICUT

OIL STOVE

Application filed June 30, 1928. Serial No. 289,359.

My invention relates to that class of stoves employing oil or a similar substance as a fuel, and an object of my invention, among others, is to provide a stove or heater that may be employed for various purposes, as for heating water, for cooking etc., which stove or heater shall be of simple construction and particularly efficient in operation.

One form of stove embodying the invention and in the construction and use of which the objects herein set out, as well as others, may be attained, is illustrated in the accompanying drawings, in which—

Figure 1 is a view in elevation of a stove embodying my invention.

Figure 2 is a top view of the same.

Figure 3 is a view, scale enlarged, in central vertical section through the stove.

In the accompanying drawings the numeral 20 5 indicates the jacket or shell of my improved stove that may be of any suitable construction and the walls of which may be insulated, if desired, as by placing an insulating material between an outer and an inner shell, as 25 shown in Figure 3 of the drawings, and this construction may apply to the bottom as well as the sides. This stove may be supported as upon legs 6 and a tank 7 for the fuel may be located at one side of the stove and resting 30 upon a distributor 8 from which a supply pipe 9 extends to the burner within the stove, said supply pipe extending upwardly through the bottom of the stove.

The heater comprises a base 10 resting upon 35 the bottom of the jacket 5 and with an outer shell 11 resting upon a shoulder on said base at the side of a flange 12. The base has a rim 13 that rests upon the bottom of the jacket and a hub 14 at its center also resting upon 40 said bottom and with openings 15 through the bottom of said base, which bottom is located above the edge of the rim 13. A support 16 of tubular construction rests upon 45 and rises from the bottom of said base to support a burner base 17, a bolt 18 passing downwardly through the burner base 17, the support 16, the hub 14 and the bottom of the jacket, as shown in Figure 3.

Grooves 19 and 20 are concentrically arranged in the burner base with shoulders at

the mouth of said grooves upon which shoulders burner shells 21—22—23—24 rest, this providing two burner flues 25—26 with an air space 27 between them. The supply pipe 9 delivers into the bottom of the groove 19 55 and a port 28 extends from this groove to the burner groove 20. These shells 21—22—23—24 are perforated in a manner common to burners of this class, the central opening 29 being closed by a cap 30 and the space between the two burner flues being closed at its upper end. Holes 31 extend through the burner base and air is supplied as through holes 32 in the jacket 5, through openings 33 in the rim of the base 10 and through the 60 holes 15 and 31 and from thence through the perforations in the shells 21—22—23—24.

A coil 34 of pipe is located within the outer shell 11, encircling the burner as a whole including the burner shells, this coil having 70 ends 35 extending through the jacket 5 and intended for connection to a tank or reservoir for holding a liquid to be used for heating purposes.

A top 36 is placed upon the upper edge of 75 the jacket 5, and this top has an opening that may be closed by a cross piece 37 and covers 38 in a manner common to stoves employed for cooking purposes.

My improved device comprises not only a 80 structure that may be used in the ordinary manner for cooking purposes, but it also embodies means for heating water, a single burner being employed for this double purpose and being so arranged as to provide a 85 very compact device and without increasing the size of the structure over what would be required were it employed for ordinary cooking purposes.

The perforations in the shells 21—22—23—24 90 have not been shown herein, but being of old and well known construction their arrangement will be well understood by a mere reference to them.

In accordance with the provisions of the 95 patent statutes I have described the principles of operation of my invention, together with the device which I now consider to represent the best embodiment thereof; but I desire to have it understood that the device 100

shown is only illustrative and that the invention may be carried out by other means and applied to uses other than those above set out.

I claim—

1. A heater comprising a jacket with a cooking top on which cooking utensils are adapted to be placed, a shell within the jacket, a burner within the shell comprising annular flue walls, means for supplying fuel to the burner, a coil surrounding said burner and disposed outwardly of the flue walls and within the shell and having means for supply of liquid to and discharge of liquid from said coil, said top having an opening overlying said shell and burner, and means for closing said opening.

2. A heater comprising a jacket with a cooking top on which cooking utensils are adapted to be placed, a shell within the jacket, a burner within the shell, means for supplying fuel to the burner, a coil surrounding said burner and disposed outwardly of the burner flame area and within the shell and having means for supply of liquid to and discharge of liquid from said coil, means for supplying air to said jacket and within said shell, said top having an opening overlying said shell and burner, and means for closing said opening.

3. A heater comprising a jacket with a cooking top on which cooking utensils are adapted to be placed, a heater base located within the jacket, a burner base supported by said heater base, means for securing both of said bases together and to the bottom of said jacket, a shell resting on said heater base, a burner within said shell comprising annular flue walls, means for supplying fuel to said burner, a coil surrounding said burner and disposed outwardly of the burner flame area and within the shell and having means for supply of liquid to and discharge of liquid from said coil, means for supplying air to said jacket and within said shell and therefrom to said burner, said top having an opening overlying said shell and burner, and means for closing said opening.

4. A heater comprising a jacket with a cooking top on which cooking utensils are adapted to be placed, a heater base located within said jacket and having a rim with an opening through said rim and base to the upper side of the latter, a shell seated on said heater base, a burner within said shell comprising annular flue walls, means for supplying fuel to said burner, means for supplying air within said jacket, a coil surrounding said burner and disposed outwardly of the flue walls and within the shell and having means for supplying liquid to and for discharging liquid from said coil, said top having an opening overlying said shell and burner, and means for closing said opening.

5. A heater comprising a casing having a

bottom and sides and a cooking top on which cooking utensils are adapted to be placed, a liquid fuel burner comprising a burner-base secured to the bottom and having an annular, burner groove formed therein, means for delivering liquid fuel to the burner groove, concentric, perforated, burner shells mounted on said base, to provide between them an annular combustion chamber above the groove having an annular discharge opening at the top for the discharge of the products of combustion beneath the cooking top, a coil surrounding the outer burner shell and having convolutions extending above the top thereof but outside the area of the annular discharge opening, means for supplying liquid to the coil and discharging the same therefrom, and a shell surrounding said coil and extending above the top thereof and having an open, upper end to permit the discharge of the products of combustion, said cooking top having an opening overlying said shell and burner and a closure for said opening.

6. A heater comprising a casing having a bottom and sides and a cooking top on which cooking utensils are adapted to be placed, a liquid fuel burner comprising a burner base having an annular, burner groove formed therein, means for delivering liquid fuel to the burner groove, concentric, perforated, burner shells mounted on said base to provide between them an annular combustion chamber above the groove having an annular discharge opening at the top for the discharge of the products of combustion beneath the cooking top, a coil having convolutions above the burner shells and outside the area of the annular discharge opening, means for supplying liquid to the coil and discharging the same therefrom, and an outer, annular shell having an open, upper end, said shell extending above the burner shells and surrounding said coil convolutions.

RALLSTON M. SHERMAN.
